UNITED STATES PATENT OFFICE

LELAND B. GREENLEAF, OF ELKHART, INDIANA, ASSIGNOR TO C. G. CONN, LTD., OF ELKHART, INDIANA, A CORPORATION OF INDIANA

TYMPANO

Application filed June 3, 1932. Serial No. 615,193.

This invention relates to musical instruments, and particularly to tympano or kettle drums.

The principal object of my invention is to provide improved means for tuning the resonant member of a tympano or kettle drum, said means including a vertically movable draught screw.

Another object of the invention is to provide improved means for tuning the resonant member of a tympano or kettle drum, said means including a draught screw and nut removably mounted in the drum pedestal.

A third object of the invention is to provide anti-friction bearing means for a tympano or kettle drum.

Another object of the invention is to provide improved means for tuning the resonant member of a tympano, said means being removable with the drum from a pedestal member.

A further object is to provide a tympano or kettle drum which is provided with improved means for tuning or tensioning the resonant member of the drum, said tuning means and drum constituting a unit, and wherein the drum and tuning means is removable from a pedestal without impairing the tension on the resonant member of the drum.

Still another object is to provide, in a tympano, a readily removable unit composed of the drum unit and the drum head tensioning means, the latter comprising a draught screw and draught nut.

Other and more specific objects of the invention are mentioned and described herein.

The preferred embodiment of my invention is illustrated in the accompanying drawings, wherein

Figure 1 illustrates a side elevational view of the tympano wherein the invention is incorporated;

Fig. 2 illustrates a fragmental elevational view of the draught screw, the drum nest or carrier, the draught screw nut, anti-friction bearing element, and the base unit or pedestal, partially in section;

Fig. 3 illustrates a section taken on line 3-3 of Fig. 2;

Fig. 4 illustrates a view of the draught screw and stop screw mounted thereon; and

Fig. 5 illustrates two views of the draught nut and dowel pins mounted therein.

Similar numerals of reference indicate like parts throughout the several views on the drawing.

Referring now to the details of the drawings the numeral 1 indicates the metal shell or body of the kettle drum, the open top whereof is normally closed by a resonating head or skin 2 which is attached to the usual annular flesh hoop 3, the latter cooperating with a circularly arranged plurality of manually actuated adjusting means whereby the drum head 2 may be stretched and tuned over the usual rim of the drum body 1 in any ordinary tuning operation on the instrument.

In the construction illustrated in Figure 1 the numeral 4 indicates generally each set of the adjusting units above referred to, each of said sets comprising the annular flanged counter hoop 5 beneath which the flesh hoop 3 is arranged; a handled screw element 6 journaled in a bearing lug 7 rigidly mounted on the hoop 5 with its screw threaded end operatively engaging in a nut 8 which is pivotally mounted in the upper arms of a double armed bell crank lever 9.

The bell crank lever 9 is pivotally mounted in the bearing element or lug 10 rigidly secured to the exterior face of the drum body 1 and the lower arms of said lever have a trunnion element 11 swivelly mounted therebetween, with which trunnion element one of a plurality of tension rods 12 is adjustably connected by screw thread connection. The rods 12 traverse suitable openings in the drum body 1 and converge upon and are operatively connected with a tension hub 13 within the drum body, said tension hub being mounted upon a reduced cylindrical portion 14 formed upon the upper end of the draught screw 15 and held against axial displacement by a washer 16 rigidly secured to a reduced extension of said bearing portion 14, said screw being rotatable in relation to said tension hub, as hereinafter described.

The bottom of the drum body 1 is rigidly

mounted upon a dish-like nest or carrier element 17 and may be secured thereto in any suitable manner, as is well known in the art, said nest or carrier member being provided 5 with the central upstanding hub 18 which is axially bored at 19 to admit the passage of the lower end of the draught screw 15 therethrough, said hub 18 projecting through a suitable aperture in the drum body, and said 10 draught screw being slidably secured within the hub bore 19 by any suitable means, such as a key 20, which key may be rigidly connected with the screw 15 and which may be in slidable engagement with the key-way 20' 15 formed in the wall of the hub bore 19, whereby said screw is rendered rotatable with the drum nest 17 and drum shell but vertically movable independently thereof.

The nest or carrier element 17 may be provided 20 with a bottom hub 21 which cooperates with the rocker member 22 which is tiltably connected with the column member 23, the latter being adjustably mounted in the base housing 24 for supporting the drum unit, 25 as hereinafter described.

The lower end of the draught screw 15 is threaded through an annular stationary draught nut 25 which is removably seated in an annular recess 26 provided in the rocker 30 member 22, the upper edge of said draught nut projecting slightly above the upper flat face of said rocker member and being engaged by the lower ring-like element of a ball bearing unit 27 which is arranged in the ball bearing 35 chamber 28 formed in hub member 21 and through which said draught screw extends.

The draught nut 25 may be held against rotation by a pair of opposed dowel pins 29 which detachably engage in suitable bearing 40 apertures 30 provided in the floor of the recess 26 in the rocker member 22. Casual disengagement of the nut 25 from its bearing recess 26 is prevented by the retaining screws 31 which may be threaded diametrically 45 through the rocker element 22 at suitable intervals, the point of each of said screws engaging in an endless circumferential groove 32 formed in the outer periphery of said draught nut.

50 The upper end of the column 23 may be forked at 33 and the cooperating forks 34 on the under side of rocker element 22 contact with said column forked section and are pivotally connected therewith by a pair of 55 pivot screws or pins 35, only one of which is illustrated, but which are well known in this art. The lower end of the draught screw 15 is arranged in the opening 36 formed in the head portion of the rocker 22 axially of the

60 nut recess 26 and in communication therewith, said opening 36 being also in communication with the space between the forks 33 of column 23 to admit downward movement of the screw 15 into said space.

65 The numeral 37 indicates a headed stop

element, of screw construction, which is provided with a reduced threaded portion 38 which is removably threaded into the lower end of the draught screw 15 axially thereof, 70 the head of said stop screw being adapted to engage the under surface of the head or body of the rocker 22 to limit upward movement of the draught screw. The head of the stop screw 37 may be provided with one or more tool recesses 39 to enable removal thereof 75 from the screw 15. The numeral 40 indicates a clamping screw suitably mounted in the forked connection between the rocker 22 and the column 23 to clamp said rocker, and thereby the drum 1, in any desired tilted position, as is well known in this art, and which forms no part of this invention.

The column 23 is vertically adjustable in the housing socket 24 and a set screw 41 may be utilized to maintain such adjustment. A plurality of pedestal or foot elements 42 may be pivotally connected with the housing member 24 in any suitable manner.

A very important feature of this invention resides in the removability of the drum unit and the means connected therewith for actuating the tuning devices 4, from the pedestal element 22, not only because such removability facilitates shipment and transportation thereof, but also because the tension, or tuned condition of the drum head 2 is not impaired to any degree by such removal or while said unit is in transit.

From the foregoing descriptive matter and the disclosure it will be evident that manual rotation of the drum body or shell causes vertical sliding movement of the draught screw 15 in the bearing bore 19, whereby the tension rods 12 and the tuning devices 4 are actuated thereby regulating the tension on the skin head 2. It will also be evident that the drum unit, the screw 15, and draught nut 25 may be bodily separated from the pedestal or base unit 22, upon removal of the stop screw 37 from the draught screw.

I claim:

1. In a tympano, in combination, a drum shell, a resonant head therefor, a head hoop encircling the drum shell rim, a plurality of tuning devices in operative engagement with said hoop, a plurality of tension rods equal in number to said tuning devices and operatively connected with the latter, and means for actuating said tension rods as a unit to actuate said tuning devices, said means comprising a draught screw which is rotatable with said drum shell, said draught screw being operatively connected with said tension rods.

2. In a tympano, in combination, a drum shell, a resonant head therefor, a head hoop encircling the drum shell rim, a plurality of tuning devices in operative engagement with said hoop, a plurality of tension rods equal in number to said tuning devices and

operatively connected with the latter, and means for actuating said tension rods as a unit to actuate said tuning devices, said means comprising an axially movable draught screw which is rotatable with said drum shell, said draught screw being operatively connected with said tension rods.

3. In a tympano, in combination, a drum shell, a resonant head therefor, a head hoop encircling the drum shell rim, a plurality of tuning devices in operative engagement with said hoop, a plurality of tension rods equal in number to said tuning devices and operatively connected with the latter, a mount for 15 said drum shell and means for actuating said tension rods as a unit to actuate said tuning devices, said means comprising a draught screw, said draught screw being operatively connected with said tension rods, said draught 20 screw being movable axially of said drum shell mount.

4. In a tympano, in combination, a drum shell, a resonant head therefor, a head hoop encircling the drum shell rim, a plurality of 25 tuning devices in operative engagement with said hoop, a plurality of tension rods equal in number to said tuning devices and operatively connected with the latter, and means for actuating said tension rods as a unit to 30 actuate said tuning devices, said means comprising an axially movable draught screw which is rotatable with said drum shell, and a tension hub mounted upon the upper end 35 of said draught screw and with which said tension rods are operatively connected.

5. In a tympano, in combination, a drum shell, a resonant head therefor, a head hoop encircling the drum shell rim, a plurality of tuning devices in operative engagement with 40 said hoop, a plurality of tension rods equal in number to said tuning devices and operatively connected with the latter, means for actuating said tension rods as a unit to 45 actuate said tuning devices, said means comprising an axially movable draught screw which is rotatable with said drum shell and a tension hub mounted upon the upper end of said draught screw and with which said tension rods are operatively connected, and stop 50 means to limit the axial movement of said draught screw.

6. In a tympano, in combination, a drum shell, a resonant head therefor, a head hoop encircling the drum shell rim, a plurality of 55 tuning devices in operative engagement with said hoop, a plurality of tension rods equal in number to said tuning devices and operatively connected with the latter, means for actuating said tension rods as a unit to 60 actuate said tuning devices, said means comprising an axially movable draught screw which is rotatable with said drum shell and a tension hub mounted upon the upper end 65 of said draught screw and with which said tension rods are operatively connected, and

stop means removably connected with said draught screw to limit the axial movement of the latter.

7. In a tympano, in combination, a drum shell, a resonant head therefor, a head hoop encircling the drum shell rim, a plurality of tuning devices in operative engagement with 70 said hoop, a plurality of tension rods equal in number to said tuning devices and operatively connected with the latter, a pedestal, anti-friction bearing means interposed between said drum shell and said pedestal, and means for actuating said tension rods as a unit to actuate said tuning devices, said means comprising a draught screw mounted 80 in said pedestal and rotatable with said drum shell, said draught screw being operatively connected with said tension rods.

8. In a tympano, in combination, a drum shell, a resonant head therefor, a head hoop encircling the drum shell rim, a plurality of tuning devices in operative engagement with 85 said hoop, a plurality of tension rods equal in number to said tuning devices and operatively connected with the latter, a pedestal, and means for actuating said tension rods as a unit to actuate said tuning devices, said means comprising a draught nut mounted in 90 said pedestal and an axially movable draught screw connected with said draught nut and rotatable with said drum shell, said draught screw being operatively connected with said tension rods.

9. In a tympano, in combination, a drum shell, a resonant head therefor, a head hoop encircling the drum shell rim, a plurality of tuning devices in operative engagement with 95 said hoop, a plurality of tension rods equal in number to said tuning devices and operatively connected with the latter, a pedestal, and means for actuating said tension rods as a unit to actuate said tuning devices, said means comprising a circumferentially 100 grooved draught nut mounted in said pedestal, an axially movable draught screw connected with said draught nut and rotatable with said drum shell, said draught screw being operatively connected with said tension rods, and means engaging said draught nut 105 groove to prevent displacement thereof from 110 said pedestal.

10. In a tympano, in combination, a drum shell, a resonant head therefor, a head hoop encircling the drum shell rim, a plurality of tuning devices in operative engagement with 115 said hoop, a plurality of tension rods equal in number to said tuning devices and operatively connected with the latter, a pedestal, and means for actuating said tension rods as a unit to actuate said tuning devices, said means comprising a circumferentially 120 grooved draught nut mounted in said pedestal, means to prevent rotation of said draught nut, and axially movable draught screw connected with said draught nut and rotatable 125 130

with said drum shell, said draught screw being operatively connected with said tension rods, and removable screw means engaging said draught nut groove to prevent displacement thereof from said pedestal.

11. In a tympano, in combination, a drum shell, a resonant head therefor, a head hoop encircling the drum shell rim, a plurality of tuning devices in operative engagement with 10 said hoop, a plurality of tension rods equal in number to said tuning devices and opera-

tively connected with the latter, a pedestal, and means for actuating said tension rods as a unit to actuate said tuning devices, said means comprising a draught nut removably mounted in said pedestal and an axially movable draught screw connected with said draught nut and rotatable with said drum shell, said draught screw being operatively connected with said tension rods.
